MULTIPLE STATION CONTROL

Arthur E. Kremiller, Glendale, Calif., assignor
to Adel Precision Products Corp., a corporation
of California

Application March 6, 1945, Serial No. 581,219

8 Claims. (Cl. 60—54.5)

1

This invention relates to hydraulic actuator systems, particularly the close manually operable type, wherein a transmitter or pump unit including a cylinder and piston, usually known as a master unit, and a receiver or motor unit likewise including a cylinder and piston, are coupled and arranged in such manner that the latter will operate to actuate or control a device, mechanism or control element, in direct response and correspondence to the manipulation of the master unit. Systems of this character are exemplified in my pending application Serial No. 499,429 filed August 20, 1943, for Compensator-accumulator unit for hydraulic systems, and Serial No. 502,343 filed September 14, 1943, for Thermal compensator for hydraulic systems.

The primary object of the present invention is to provide a system of the character described which is constructed and arranged so that a receiver or motor unit operatively connected to a device, mechanism, control lever or member to be actuated thereby, is subject to the desired selective operation responsive to manipulation of any one of a plurality of master units located at control stations remote from one another, for example, in aircraft and surface craft and at other places where it is desirable to have a plurality of control stations remote from one another and the motor unit. In the case of a ship, for example, one of the master units may be located in the wheel house, another of the master units on the flying bridge, and a third master unit in the engine room, while the motor unit is located where it is desired to actuate a device, mechanism or control, thereby making possible an accurate and quick control, for example, of an engine throttle, from any of the control stations thus established.

Another object of this invention is to provide a multiple control system of the character described which is of simple and light weight construction, may be readily and easily installed and will be accurate and reliable as to performance.

A further object is to provide a system such as described in which each master unit will operate in direct response and correspondence to the one of the plurality of such units which is manipulated to operate the system, thereby disposing the operating lever or handles of such units in corresponding positions whereby at each control station a tell-tale indication is had as to the nature and extent of operation of the motor unit responsive to given manipulation of any one of the master units.

2

Yet another object of my invention is to provide a multiple control system such as described which is simplified and rendered highly efficient by reason of being made up of a plurality of separate closed hydraulic systems which by means of a novel mechanical coupling of master units of such systems at one of the control stations causes such systems to operate in unison responsive to manipulation of any one of the master units at the several control stations.

With the foregoing objects in view, together with such other objects and advantages as may subsequently appear, the invention resides in the parts and in the combination, construction and arrangement of parts hereinafter described and claimed, and illustrated by way of example in the accompanying drawing, in which:

Fig. 1 is a schematic view of a system embodying the present invention, with certain parts and elements shown in section and other parts and elements in elevation, for the sake of clarity of illustration;

Fig. 2 is a fragmentary sectional view of the hydraulic locking means of the motor unit.

Referring to the drawing more specifically it will be apparent that a system embodying my invention will include a plurality of transmitter or master units for controlling and operating a receiver or motor unit and the present embodiment provides for three master units designated, A, B and C respectively and an actuator or motor unit D which latter may be connected to a mechanism or element (not shown) which is to be operated or controlled thereby.

Each of the master units A and C is identical and consists of a cylinder 1 in which a piston 2 is arranged to be moved responsive to manipulation of an operating handle or lever 3 connected by links 4 to the piston rod 5.

The master unit B consists of identical cylinders 6 and 7 corresponding in size and capacity to the cylinders of units A and C and containing pistons 8 and 9 and piston rods 10 and 11. The cylinders 6 and 7 are united or fastened together in side by side relation and the rods 10 and 11 are mechanically coupled to one another for joint and corresponding movement responsive to a common operating handle 12. This handle is fixed to a cross head 13 secured to and extending between two levers 14 connected to the piston rods 10 and 11.

The actuator or motor unit D includes a cylinder 15 similar to cylinders 1, 6 and 7 and provided with a piston 16 and a piston rod 17. This piston rod is coupled by a link 18 to a lever 19

to which a rod 20 is connected whereby a device, throttle or other element may be moved when the motor unit piston is moved.

In association with this motor unit is a hydraulic locking means which will prevent externally applied loads transmitted through the lever 19 from moving the piston 16 and likewise moving the pistons in the several master units while holding the motor actuated mechanism or element in the desired position. This hydraulic locking means includes spring loaded valves 21 and 22 arranged to control the flow of fluid through passages 23 and 24 leading through the walls of the motor cylinder to opposite ends of said cylinder. These valves seat against tubular seat members 25 and are arranged to open responsive to pressure of operating fluid delivered to the motor unit from the other units of system, but will close incident to fluid pressure applied thereto as when the piston 16 tends to move responsive to external forces applied through the lever 19. A valve operating piston 26 is reciprocable in a cylinder bore 27 between the passages 23 and 24 whereby the piston 26 will respond to operating fluid directed through either of the passages. Projections 28 on the piston 26 are arranged to contact and unseat the valves 21 and 22. If valve 21 opens responsive to operating fluid delivered to the motor unit from the other units through passage 23, the piston 26 will be forced to the right and open valve 22 which latter then allows return fluid to flow from the motor cylinder through passage 24. When valve 22 is opened by pressure fluid delivered through passage 24, the piston 26 will move to the left and open valve 21 as the "return" valve.

In the present embodiment of my invention there are provided two closed hydraulic systems which act in unison. One of these systems includes the master unit A and the cylinder 6 of the master unit B, there being dual fluid lines 29 and 30 connected at their ends to corresponding ends of the cylinders 1 and 6 so that fluid displaced by the piston 2 of unit A when the latter is manually operated will be transmitted through one of these lines to cylinder 6 to move piston 8 in correspondence to movement of the manually actuated piston 2. Return fluid from cylinder 6 then passes through the other of the fluid lines back to cylinder 1. When on the other hand, the unit B is manipulated the piston 8 therein displaces fluid to the cylinder 1 of unit A and moves piston 8, while return fluid from cylinder 1 flows to the cylinder 6.

The other of the two closed systems hereof includes the cylinder 7 of master unit B, the motor unit D and the master unit C. One fluid line 31 runs from the right end of cylinder 7 to the left end of cylinder 15 of the motor unit. Another fluid line 32 leads from the right end of motor cylinder to the left end of the cylinder 1 of the master unit C.

From the right end of the cylinder of unit C a fluid line 33 leads to left end of cylinder 7 of master unit B thereby completing the second closed circuit embodied in my system.

The mechanical linkage of the cylinders 6 and 7 of unit B as provided by means of the levers 14 and cross head 13 to which latter the handle 12 is connected, make the two closed systems interdependent for operation in unison in accordance with this invention without hydraulically coupling such systems, so that when either system is operated the other will respond accordingly.

An accumulator-equalizer unit E is connected to the lines 29 and 30 by means of fluid lines 34 and 35 respectively and an identical accumulator-equalizer unit F is connected to the fluid lines 31 and 33 by means of the fluid lines 36 and 37 respectively. These accumulators are identical and each is provided with a compressed air chamber 38 having a valved intake 39, separate reservoir chambers 40 and 41 and a double piston 42 forced by air pressure to create a fluid pressure in the reservoir chambers and therefore maintain an initial pressure throughout the closed system associated with the accumulator. This pressurizing of the entire system prevents entrance of air into the system and assures a more efficient operation of the system as a whole. The accumulators also compensate for thermal expansion and contraction so as to maintain the proper amount of fluid in each part of the system at all times regardless of extreme temperature variations. Each accumulator is provided with an indicator 43 to show the extent of initial pressure in the system and the amount of fluid in the accumulator itself.

The cylinders of the several master and motor units have fluid by-pass valves 44 and associated passages 45 to provide for synchronizing the system in the manner well known in the art. The system is filled through the accumulators by means of normally closed filling ports and bleed ports which are not here shown or may be filled in any suitable manner. This arrangement and the method of filling are known in the art and form no part of the present invention.

Operation

Assuming that master unit A is located in the wheel house of a ship, master unit B is located on the flying bridge, master unit C is located in the engine room and the motor unit D is arranged to operate some control on the ship such as an engine throttle, it is seen that the motor unit may be operated by manipulating any one of units A, B and C. If unit A is manipulated to move the piston 2 therein, for example, to the left of the position shown in Fig. 1, in order to operate the motor unit to open the throttle, the fluid displaced by the piston 2 in unit A will set up a pressure in the line 29 which is connected to the right end of cylinder 6 in unit B, whereupon the piston 8 of unit B will be moved to the left in correspondence to the movement of the piston in unit A. Fluid displaced by piston 8 is delivered to unit A through line 30. As the piston 8 is mechanically connected to piston 9 of the other cylinder 7 of unit B, through the levers 14 and cross head 13 it is seen the piston 9 will move with piston 8 to the left and displace fluid through the line 33 to the right end of cylinder 1 of unit C. The piston 1 of unit C will also move to the left and displace fluid through line 32 to the right end of cylinder 15 of the motor unit D thereby moving the piston 16 of motor unit to the left and through the lever 19 and rod 29 operate the throttle, not shown. Fluid displaced by the motor piston 16 now returns through line 31 to the right end of cylinder 7 of unit B.

In this operation of unit A the pistons of master units B and C move the same extent as the manually operated piston of unit A and serve as tell-tale indicators at their respective stations of the extent of operation effected at the station at which unit A is located.

When unit A is operated to move the piston 2 thereof to the right fluid is displaced through

line 30 to lift end of cylinder 6 of unit B thereby moving the piston 8 to the right and displacing fluid from right end of cylinder 6 through line 29 to the left end of the cylinder of unit A. Piston 9 likewise moves to the right, with piston 8 and displaces fluid through line 31 to the left end of cylinder 15 of motor unit D thereby moving the slave piston 16 to the right and operating the lever 19 and rod 20 accordingly. At the same time, fluid displaced by the motor piston 16 will flow through line 32 to the left end of the cylinder 1 of unit C thereby moving piston 2 of unit C to the right and causing fluid to flow through line 33 back to the left end of cylinder 7 of unit B.

When unit B is operated, for example, to move the pistons 8 and 9 thereof to the left, the cylinder 7 and piston 9 thereof operate to displace fluid for operating units C and D in the same manner as when unit A is moved to the left, while cylinder 6 and piston 8 operate to direct fluid to and operate piston 2 of master unit correspondingly. Thus the operating handles 3 of units A and C will move to the same positions as handle 12 of unit B.

When unit B is operated to move its pistons 8 and 9 to the right, the cylinder 7 and piston 9 operate to direct operating fluid for units C and D in the same manner as when unit A is operated to move its position to the right while cylinder 6 and piston 8 operate to actuate unit A to the right in correspondence to the operation of unit B.

When unit C is operated to move its piston to the left, fluid is displaced through line 32 to the left end of motor cylinder 15 moving piston 16 and lever 19 and rod 20 correspondingly, while fluid from the left end of motor cylinder 15 is displaced through line 31 to the right end of cylinder 7 of unit B, whereby the piston 9 moves to the left and displaces fluid through line 32 to the right end of cylinder 2 of unit C. At the same time cylinder 6 and piston 8 of unit B are operated in correspondence to cylinder 7 and piston 9, thereby exchanging fluid with unit A and moving the latter in correspondence to units C and B.

When unit C is operated to move its piston 2 to the right, fluid is displaced through line 33 to the left end of cylinder 7 of unit B and moves piston 9 to the right, thereby displacing fluid through line 31 to the left end of the slave cylinder 15 and moving piston 16, lever 19 and rod 20 accordingly. From the right end of slave cylinder 15 fluid flows through line 32 to the left end of cylinder 2 of unit C. When piston 9 is moved to the right, the piston 8 is also moved to the right thus causing an exchange of fluid between units A and B and the movement of the pistons thereof in correspondence to the movement of pistons 9 and 2 of units B and C.

While I have shown and described a specific embodiment of my invention, I do not limit myself to the exact details of construction set forth, and the invention embraces such changes, modifications and equivalents of the parts and their formation and arrangement as come within the purview of the appended claims.

I claim:

1. In a hydraulic actuator system with multiple control stations, a closed hydraulic system including a pair of master units each of which embodies a cylinder, a piston therein, and a manipulating means by which the piston may be moved in opposite directions; fluid lines connecting the cylinders of said units so that upon op-

eration of the piston in either unit the piston of the other unit will be operated in correspondence to that of the manipulated piston; a second closed hydraulic system including two master units each of which embodies a cylinder, a piston therein and a manipulating means for moving the piston in opposite directions; a motor unit embodied in the second system including a cylinder, a piston therein and a drive means responsive to the piston and adapted to be operatively connected with a mechanism or control element to be operated by the actuator system, fluid lines connecting the cylinders in the second system so that the pistons therein will move correspondingly responsive to actuation of the manipulating means of any one of the master units in the second system; and means mechanically joining the manipulating means of one of the master units of the first named closed system with the manipulating means of one of the master units of the second closed system whereby the pistons of said two connected units will operate in unison and the other pistons in the two systems will operate correspondingly responsive to actuation of the mechanically connected manipulating means as well as responsive to the actuator of the manipulating means of any other master units in the closed systems.

2. In a hydraulic actuator system with multiple control stations, including a pair of master units each of which embodies a cylinder, a piston therein, and a manipulating means by which the piston may be moved in opposite directions; fluid lines connecting the cylinders of said units so that upon operation of the piston in either unit the piston of the other unit will be operated in correspondence to that of the manipulated piston; a second closed hydraulic system including two master units each of which embodies a cylinder, a piston therein and a drive means responsive to the piston and adapted to be operatively connected with a mechanism or control element to be operated by the actuator system, fluid lines connecting the cylinders in the second system so that the pistons therein will move correspondingly responsive to actuation of the manipulating means of any one of the master units in the second system; means mechanically joining the manipulating means of one of the master units of the first named closed system with the manipulating means of one of the master units of the second closed system whereby the pistons of said two connected units will operate in unison and the other pistons in the two systems will operate correspondingly responsive to actuation of the mechanically connected manipulating means as well as responsive to the actuator of the manipulating means of any other master units in the closed systems.

3. In a hydraulic actuator system with multiple control stations, a closed hydraulic system including master units each of which embodies a cylinder, a piston therein, operating means by which the piston may be moved in opposite directions, and fluid lines connecting the cylinders of said units so that pistons of said units will be simultaneously moved responsive to actuation of the operating means of any one of said master units; a second closed

hydraulic system including master units each of which embodies a cylinder, a piston, an operating means for reciprocating the piston, and fluid lines connecting the cylinders in the second system so that the pistons therein will move simultaneously upon actuation of the operating means for any one of the second system master units; a hydraulically responsive motor unit connected with the fluid lines in one of said closed systems including a cylinder, a piston therein adapted for operative connection with a control element or mechanism to be operated by the actuator system; the connections of the motor unit cylinder with said one closed system being such that the motor unit piston will be moved responsive to movement of the piston of any of the master units in said one closed system; and a means of operative connection between certain master units of the first named closed system and the second closed system whereby the motor unit piston becomes responsive to movement of any one of the master unit pistons in the first named and second closed systems.

4. In a hydraulic actuator system with multiple control stations, a closed hydraulic system including master units each of which embodies a cylinder, a piston therein, operating means by which the piston may be moved in opposite directions, and fluid lines connecting the cylinders of said units so that pistons of said units will be simultaneously moved responsive to actuation of the operating means of any one of said master units; a second closed hydraulic system including master units each of which embodies a cylinder, a piston, an operating means for reciprocating the piston and fluid lines connecting the cylinders in the second system so that the pistons therein will move simultaneously upon actuation of the operating means for any one of the second system master units; a hydraulically responsive motor unit connected with the fluid lines in one of said closed systems including a cylinder, a piston therein adapted for operative connection with a control element or mechanism to be operated by the actuator system; the connections of the motor unit cylinder with said one closed system being such that the motor unit piston will be moved responsive to movement of the piston of any of the master units in said one closed system; and means connecting one of the master units of the first named system with one of the master units of said second system so that the pistons of said connected master units will move responsive to movement of any one of the other master unit pistons in both of said closed systems.

5. In a hydraulic actuator system with multiple control stations, a closed hydraulic system including master units each of which embodies a cylinder, a piston therein, operating means by which the piston may be moved in opposite directions, and fluid lines connecting the cylinders of said units so that pistons of said units will be simultaneously moved responsive to actuation of the operating means of any one of said master units; a second closed hydraulic system including master units each of which embodies a cylinder, a piston, an operating means for reciprocating the piston and fluid lines connecting the cylinders in the second system so that the pistons therein will move simultaneously upon actuation of the operating means for any one of the second system master units; a hydraulically responsive motor unit connected with the fluid lines in one of said closed systems

including a cylinder, a piston therein adapted for operative connection with a control element or mechanism to be operated by the actuator system; said motor unit being connected in the fluid lines of said one closed system so that the motor unit piston is subject to movement simultaneously with the pistons in the master units of said one system; and means of operative connection between said closed systems constructed and arranged so that responsive to actuation of the operating means for any of the master unit pistons all of said pistons will be simultaneously moved.

6. In a hydraulic actuator system with multiple control stations, a closed hydraulic system including master units each of which embodies a cylinder, a piston therein, operating means by which the piston may be moved in opposite directions, and fluid lines connecting the cylinders of said units so that pistons of said units will be simultaneously moved responsive to actuation of the operating means of any one of said master units; a second closed hydraulic system including master units each of which embodies a cylinder, a piston, an operating means for reciprocating the piston and fluid lines connecting the cylinders in the second system so that the pistons therein will move simultaneously upon actuation of the operating means for any one of the second system master units; a hydraulic motor unit connected with the fluid lines of one of said systems so that it is responsive to movement of any one of the pistons in said one system and while being thus actuated will force fluid through one of said lines for moving a piston in one of the master units of said one system; and means of operative connection between said systems constructed and arranged so that responsive to operation of the operating means of any one of said master units the motor unit will be actuated.

7. In a hydraulic actuator system with multiple control stations, a closed hydraulic system including master units each of which embodies a cylinder, a piston therein, operating means by which the piston may be moved in opposite directions, and fluid lines connecting the cylinders of said units so that pistons of said units will be simultaneously moved responsive to actuation of the operating means of any one of said master units; a second closed hydraulic system including master units each of which embodies a cylinder, a piston, an operating means for reciprocating the piston and fluid lines connecting the cylinders in the second system so that the pistons therein will move simultaneously upon actuation of the operating means for any one of the second system master units; a hydraulic motor unit connected with the fluid lines of one of said systems so that it is responsive to movement of any one of the pistons in said one system and while being thus actuated will force fluid through one of said lines for moving a piston in one of the master units of said one system; means of operative connection between said systems constructed and arranged so that responsive to operation of the operating means of any one of said master units the motor unit will be actuated; and valve means associated with fluid lines leading to said motor unit operating to hydraulically lock said motor unit against movement except when pressure fluid is conducted to said motor unit through a line leading thereto.

8. In a hydraulic actuator system with multiple control stations, a closed hydraulic system including master units each of which embodies

a cylinder, a piston therein, operating means by which the piston may be moved in opposite directions, and fluid lines connecting the cylinders of said units so that pistons of said units will be simultaneously moved responsive to actuation of the operating means of any one of said master units; a second closed hydraulic system including master units each of which embodies a cylinder, a piston, an operating means for reciprocating the piston, and fluid lines connecting the cylinders in the second system so that the pistons therein will move simultaneously upon actuation of the operating means for any one of the second system master units; a hydraulic motor unit connected with the fluid lines of one of said systems so that it is responsive to movement of any one of the pistons in said one system and while being thus actuated will force fluid through one of said lines for moving a piston in one of the master units of said one system; and means of

10

5 operative connection between said systems constructed and arranged so that responsive to operation of the operating means of any one of said master units the motor unit will be actuated; and means in each system for maintaining an initial fluid pressure therein and arranged to receive fluid from the system and discharge fluid into the system responsive to thermal expansion and contraction.
